US0D1061511S

(12) **United States Design Patent** (10) **Patent No.:** **US D1,061,511 S**
Li (45) **Date of Patent:** ** Feb. 11, 2025

(54) **SMARTWATCH**

(71) Applicant: **BEIJING XIAOMI MOBILE SOFTWARE CO., LTD.**, Beijing (CN)

(72) Inventor: **Jianting Li**, Beijing (CN)

(73) Assignee: **BEIJING XIAOMI MOBILE SOFTWARE CO., LTD.**, Beijing (CN)

(**) Term: **15 Years**

(21) Appl. No.: **29/878,224**

(22) Filed: **Jun. 19, 2023**

Related U.S. Application Data

(62) Division of application No. 35/513,867, filed on Jan. 11, 2022 (U.S. filing date under 35 U.S.C. 384), and (Continued)

CLAIM

The ornamental design for a smartwatch, as shown and described.

DESCRIPTION

FIG. 1 is a front view of a smartwatch showing the new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a front perspective view thereof; and,

FIG. 8 is a back perspective view thereof.

The broken lines shown in the drawings illustrate portions of the smartwatch and form no part of the claimed design.

1 Claim, 8 Drawing Sheets

Related U.S. Application Data
